UNITED STATES PATENT OFFICE.

FRANZ KASPAR, OF PRAGUE, CZECHOSLOVAKIA.

DEVICE FOR SEVERING AND APPLYING STAMPS OR THE LIKE TO ENVELOPES OR OTHER SURFACES.

Application filed August 20, 1923. Serial No. 658,421.

To all whom it may concern:

Be it known that I, FRANZ KASPAR, citizen of Czechoslovakia, residing at Havlickovo Namesti c. 2, Prague, Czechoslovakia, have 5 invented a new and useful Device for Severing and Applying Stamps or the like to Envelopes or Other Surfaces, of which the following is a specification.

This invention relates to devices for 10 severing stamps, labels and the like from strips and affixing them to envelopes and similar articles.

In United States Patent No. 1,388,817 I 15 have described a device of this kind in which the feeding of the strip of stamps or the like wound up in the form of a roll and adapted to be severed and stuck in position is effected by a roller provided with teeth, the teeth being adapted to engage with 20 the perforations which separate the separate stamps or the like from each other. This device, however, has the disadvantage that it is only capable of being used for stamps of a particular size and with particular 25 perforations so that it is necessary to change the feed device when stamps of different dimensions are used.

This disadvantage is obviated according 30 to the present invention by reason of the fact that the feeding of the stamps or the like is effected by a kind of brush so that the device can be used for any size of stamps or the like without its being necessary to change the feed device.

35 Constructional embodiments of the invention are illustrated in the accompanying drawings in which:—

Figure 1 is a somewhat diagrammatic and 40 fragmentary sectional elevation of part of a stamp severing and affixing machine provided with a feeding member in accordance with the invention and in which it is to be assumed that the operating handle is depressed.

45 Figure 2 shows a somewhat different construction partly in side elevation and partly in section with the handle in the normal position and

Figure 3 is a front elevation.

50 The implement itself is identical with that described in the hereinbefore mentioned patent and consists mainly of two parts, viz: the frame 1 and the punch 2, the latter

being mounted for vertical reciprocating movement within said frame. 55

To the frame there is affixed a horizontal pin 72 on which is fulcrumed the upper end of a lever 13' having spaced, upper and lower fingers 15 and 14, and also having an elongated lug 16; the upper finger 15 being 60 provided with an inwardly-extending terminal 52. The pin 72 has coiled around it a compressed or tensioned spring which presses lever 13' laterally against the frame, thus acting as a friction brake for said lever 65 and, hence, for the moistening device 3' carried thereby. This device is in the nature of a lever which is hinged at one end to a horizontal pin 80 attached to the lower end of lever 13', and is pressed yieldingly upward by a torsion spring coiled around said pin. In its normal position represented in Fig. 2, the lever is engaged by a detent 47, which catches under a roller 46 on the lever. 70

On the casing 1 there is secured to a flange 3 (Fig. 1) by means of the screw 10 a flexible holder 4 which carries the feed brush 7 consisting of a number of resilient thin rods placed side by side and having their lower ends bent. In this construction the holder 80 and brush are flexible as a whole. 75

In the construction shown in Figs. 2 and 3 the holder itself is rigid.

The punch 2 is provided with a guide-piece 57, which is mounted to slide in a slot 85 6 formed in the frame, and is further provided with a tubular stem 8 fitting in a guide sleeve 11 and terminating in a suitable knob or handle 15'. The punch is normally maintained in elevated position by a spring not 90 shown and a pad may be employed to cushion the punch at the limit of its upward movement. 95

The moistener 3' is operated by the punch through the intermediary of a roller 12' attached to the guide 57; said roller being designed to travel along the inner edges of the fingers 15 and 14 on the operating lever 13' which are so curved as to produce a swinging or rocking movement of said lever 100 in one direction or the other, due to the pressure exerted thereagainst by the roller, according as the latter is engaged with the lower or the upper finger. The engagement of the roller with the lower finger is effected 105 during the descent of the punch, as will be

understood; but it does not take place until the last half of the stroke, the roller travelling along the straight edge of the portion of the lever between the two fingers during 5 the first half of the stroke, at which time the swinging movement of the lever is prevented by the engagement of the lug 16 with the in-turned end of a keeper 17 attached to the stud or axle whereon the roller turns. 10 The keeper disengages said lug just about the time that the roller starts its movement along the curved edge of the lower finger, and thereafter the lever is forced outwardly or away from the frame the provision of the 15 lug and keeper thus avoiding premature movement of the operating lever, which latter is stopped at the conclusion of its outward movement by the engagement of the terminal 52 of finger 15 with a lug on the frame, and is retained in such position by 20 the engagement of the nose 19 on the moistener lever 3 with the detent 47 on the frame.

The operating lever remains in the position just mentioned during the first half of 25 the succeeding up-stroke of the punch and until roller 12' strikes against the curved edge of the upper finger 15, whereupon the pressure exerted by the roller against said edge forces the lever to swing back toward 30 the frame into its original position.

The strip 31 of stamps or the like is wound up on a suitable reel which is disposed within a drum or container 9 having a peripheral opening for the passage of the strip therethrough. After leaving the drum the strip is led through a guide passage 6 constituting one element of the feed mechanism, and then passes through an opening 14' formed in the movable member or knife 51 of the 40 cutting or severing mechanism as subsequently explained to a position beneath the presser pad or member 21 situated on the bottom of the punch.

The improved feeding mechanism according to this invention comprises a guide passage 6, having its lower end suitably shaped, through which is guided a perforated strip of stamps. The front wall of this passage is provided with a slot extending longitudinally thereof on the upper end of which rests a resilient closing plate 12 of which the lower bent end passes through the passage and extends to the solid rear wall.

The bent ends of the feed brush 7 also 55 pass through the slot and extend to the rear wall of the passage. In the normal position of the device these brush ends are almost at the end of the passage.

By depressing a lever 5 the lower end of 60 the closing plate 12 is withdrawn from the rear wall of the passage thus exposing the passage into which is now introduced the strip of stamps to such a distance that the first row of horizontal perforations lies adjacent the lower edge of the closing plate.

By releasing the lever 5 the edge of the plate again bears against the rear wall thus holding the strip of stamps.

The improved feeding mechanism operates substantially as follows:—Upon depression of the handle of the punch 2, the guide passage 6 together with the strip of stamps (shown in chain dotted lines) moves past the feed brush of which the lower ends are ground off in such a manner that they do 70 not engage with the perforations when the strip of stamps is moved past them. On further depression the feed brush passes over the retaining device 12 holding the strip of stamps. 75

On the succeeding return movement of the punch 2 the passage 6 together with the strip of stamps again moves upwards, whereby some of the rods of the feed brush 7 engage with their ends in the perforations of the strip of stamps 9 whilst the remaining brush rods, which do not engage directly with perforations, press the strip of stamps against the rear wall of the passage and prevent the stamps from 80 being threaded on the rods passing into the perforations. The mechanism by which the stamps or sections of paper are severed is the same as that described in my aforementioned patent and comprises, in addition 85

to the knife 51, a second knife 41 which is rigidly fixed to the punch, as will be apparent from Fig. 2, and with respect to which the knife 51 is movable. The knife 41 terminates approximately flush with the under face of pad 21, but the movable knife 51 projects some distance below said pad and is pressed yieldingly downward by the action of a spring and, at the same time, is pressed against the fixed knife by 90 suitable means. The spring exerts its downward pressure directly against a laterally projecting lug which is integrally or otherwise rigidly connected with knife 51 and which has a depending finger that rests upon the adjacent end of the resilient channel member 37, the pressure of said spring being sufficient to flex the channel member 95 downward and thereby bring its mouth directly opposite the opening 14' formed in knife 51. The member 37 is preferably constructed of thin flexible or resilient metal, and is fastened at its rear end by means of screws 100 105 110 115 120 125 130 37' or the like to the punch. When the punch descends, the cutting mechanism moves with it, the two knives remaining relatively stationary until the lower edge of knife 51 strikes against the wall of support or table. Thereafter, during the continued movement of the punch, knife 51 will be forced upward against the action of the spring and as said knife yields, the channel member 37 also moves upward, carrying the strip with it into position to be ultimately severed by the coaction be-

tween the two knives. During the subsequent return movement of the punch, the knife 51 is restored to its former position under the action of the spring and at the same time the resilient channel member 37 is again pressed down into position to aline its mouth with the opening in said knife.

The complete operation, briefly stated is as follows: During the first half of the 10 down-stroke of the punch, the operating lever 13' is held against movement by the engagement of the keeper 17 with lugs 16, and just when the disengagement of those two parts takes place, the roller 12' commences its travel along the curved upper edge of the lower finger 14 on said lever. This has the effect of camming the lever outwardly of the frame 1 of the implement, during which movement the moistener 3 20 moves outwardly along with said lever, the pad 22 thereon being pressed against the under surface of the stamp by the action of a spring and drawn along said surface. The outward movement of the lever continues until the pad has left the stamp 25 and the nose 19 of the moistener has been brought into engagement with the lip or detent 47 on the frame, the stopping of the lever being effected by the engagement 30 of the terminal 52 with lug 49. During the continued movement of the punch, the moistened stamp is pressed against the top-most envelope on the pile by the pad 21, and is severed from the strip by the coaction 35 between the fixed and movable knives 41 and 51 as the latter knife ascends the two operations taking place close together by the lug 62.

When the pressure upon the punch is removed a spring forces the punch upward and during this stroke the movable knife 51 and the channel member 37 resume their former positions while some of the rods of the feed brush 7 engage with their ends in

the perforations of the strip of stamps 31 45 to unwind stamps from the roll. The operating lever 13', during the first part of the up-stroke of the punch remains in the position into which it was moved during the preceding down-stroke of the punch; 50 but during the last half of the up-stroke the roller 12' on the punch engages the upper finger on the lever and thereupon forces the latter, and with it the moistener 3', to move inwardly toward the frame 55 this movement of the moistener disengaging its nose 19 from the detent 47 which thereupon engages the roller 46 when the lever completes its inward movement. The implement is then ready for another operation.

What I claim and desire to secure by Letters Patent of the United States is:—

1. A device of the class described for severing and affixing postage stamps, labels 65 and the like supplied in strip form comprising in combination with the casing of the device a feed brush consisting of separate resilient small rods placed side by side and having their ends bent and suitably ground off, a fixed holder for said brush, a movable plunger having a strip guiding passage formed therein and a resilient strip-retaining device, the brush ends sliding in the said passage and on the return movement of the plunger engaging with the perforations of the strip and holding the latter thus unrolling the strip from its roll, the said strip being already held in the upper part of the passage by the 70 pressure of the aforesaid resilient strip retaining device against the rear wall of the 75 said passage.

2. A device as claimed in claim 1 in which the holder of the feeding brush is flexible. 85

FRANZ KASPAR.
